UNITED STATES PATENT OFFICE.

EDWARD S. EVANS, OF DETROIT, MICHIGAN.

TWO-PART TIE DOWN.

Application filed December 10, 1926. Serial No. 153,841.

This invention relates to certain new and useful improvements in tie downs for use in the shipment of automobiles and has for its primary object to provide a tie down that is initially anchored to a railroad car floor and is subsequently moved into tie down relation with a part of an automobile after the same has been moved to a position above the previously anchored tie down to eliminate the necessity of a person crawling beneath the automobile for later anchoring the tie down in position.

An important object of this invention is to construct a tie down of the above type in two sections, the tie down being of metallic strap formation with a foot carried by each section adapted to be anchored to a car floor or other support prior to the positioning of a car in its shipping location and with the two strap sections of the tie down subsequently engaged with a part of an automobile, such as an axle or wheel hub with the adjacent ends of the two sections of the tie down drawn toward each other and secured together in any suitable manner by a character of fastening devices or the most simple method known in the art as the "signode seal".

It is also an object of the invention to use a two part wire tie down with one end of each wire part positioned to provide a foot or associated with a sheet metal foot with the other end of the wire parts twisted together and with the twisted portions aligned with one leg of the tie down.

With the above and other objects in view that will appear as the nature of the invention is better understood, the same consists in the novel combination and arrangement of parts hereinafter more fully described, shown in the accompanying drawing and claimed.

In the accompanying drawing, wherein like reference characters indicate corresponding parts throughout the several views.

Figure 1 is a fragmentary side elevational view of the front end of an automobile with the left front wheel removed, the axle bar shown in section and the two part tie down anchored to the floor and engaged with the axle;

Figure 2 is a side elevational view of the tie down, partly broken away showing the meeting ends of the two parts of the tie down overlapped and in position to be secured together;

Figure 3 is a fragmentary elevational view showing the overlapped meeting ends of the two parts of the tie down with curved edge flanges carried by one part of the tie down 60 overlying the other part of the tie down;

Figure 4 is a fragmentary elevational view, similar to Figure 3 showing the opposite edges of the overlapped ends of the two parts of the tie down pressed inwardly 65 or toward each other to form an interlocking connection therebetween;

Figure 5 is a perspective view of one part of the tie down showing the anchoring foot carried thereby; 70

Figure 6 is a view similar to Fig. 1 showing the tie down formed of wire;

Figure 7 is a side elevational view of the tie down;

Figure 8 is a fragmentary elevational view 75 showing the ends of the wire tie down twisted together;

Figure 9 is a top plan view, partly in section of a wire tie down foot; and

Figures 10 and 11 show perspective views 80 of metallic anchoring feet associated with the wire tie down.

In the shipment of automobiles, it is customary to rigidly anchor the automobile to the car floor or rolling stock to hold the 85 automobile against movement, but the majority of all known methods previously employed consists of first moving the automobile into position in the car and subsequently anchoring the automobile to the car floor 90 which necessitates a person crawling beneath the automobile and in a crowded and cramped position it is required to anchor the tie down to the car floor, such methods in many instances proving most unsatisfactory. The 95 gist of the present invention resides in the provision of a two part tie down of metallic strap formation and designed in a manner to permit the initial anchoring of the tie down to the floor of a car, then rolling the 100 automobile into its shipping position and finally attaching the two part tie down to a part of the automobile, such as the axle or wheel hub with the meeting ends of the two parts of the tie down finally secured together for safe anchorage of the automobile.

One form of the invention to accomplish the above objects is shown in Figures 1 to 5 wherein there is provided a two part tie down of metallic strap formation comprising the parts 1 and 2 with an anchoring foot carried by one end of each part that 110

may be of any design desired, but herein illustrated in the form of the figure 4 and comprising the section 3 bent at right angles to the part 2 with the outer end of the section 3 return bent at an angle thereto as at 4 while the end of the section 4 is bent at angle as at 5 to overlie the section 3 at right angles and disposed at the lower end of the part 2. The several sections of the foot are provided with openings 6 for the passage of nails, screws or other fastening means.

The part 2 of the tie down is of relatively short length when compared with the tie down part 1 and being of metallic strap formation as illustrated carries at its opposite side edges at the upper end inwardly directed overlying edge flanges 7 to overlie the end 1^a of the part 1 when the ends of the two parts of the tie down are assembled as shown in Figure 3. The overlapped ends of the two parts of the tie down may be secured together in any suitable manner, the method preferred being to forcibly press the opposite edges of the overlapped ends of the two parts of the tie down toward each other to form an interlocking connection 8 between the overlapped ends as shown in Figure 4.

As previously stated, the two parts 1 and 2 of the tie down are anchored to the floor F of a railroad car and the automobile A then is moved into position to be anchored, and as shown in Figure 1 the two part tie down is engaged with the axle bar B. The parts 1 and 2 of the tie down are of relative length to dispose the meeting overlapped ends thereof that are to be connected, substantially midway between the engaged part B of the automobile and the car floor F and at the outer end of the automobile. With the tie down so disposed, the meeting ends are conveniently positioned to permit interlocking engaging the same in any suitable manner without the necessity of requiring a person to crawl upon the floor of the car beneath the automobile.

In the form of the invention shown in Figures 6 to 11, the two part tie down is formed of wire and comprises two parts 10 and 11, the part 10 being of a length to be placed in engagement with the part of an automobile to be anchored with the end thereof extended downwardly as shown in Figures 6 and 7 for association with the upper end of the part 11 so that the engagement between the two parts is present in one of the upright legs of the tie down.

As shown in Figure 9, the lower end of each part 10 and 11 of the wire tie down is bent, twisted and looped to form an anchoring foot 12 by which the tie down is secured to a car floor or other support. As shown in Figure 10, the lower end of the tie down leg is associated with a metallic anchoring foot 13 that has a pair of spaced openings

therein through which the tie down is passed. In the form of tie down foot shown in Figure 11, there is provided a metallic plate 14 that is longitudinally and upwardly grooved as at 15 to provide a clearance for the lower end of the wire tie down leg that is reversely bent at its terminal end to overlie the plate 14.

With the two parts 10 and 11 of the wire tie down anchored to a car floor or other support, the car A is moved into position to be engaged by the wire tie down and when so disposed, the ends of the two parts 10 and 11 are positioned in overlapping relation as shown in Figure 7. The overlapped ends of the two parts of the wire tie down are then twisted together in spiral or screw formation as at 16 and shown more clearly in Figure 8 and which twisting may be accomplished by any suitable hand device or in any way preferred.

While there is disclosed a tie down that may be formed of sheet metal or wire, it is to be understood, that any character of material may be employed in the manufacture thereof, the main idea being to form the tie down of two parts with an anchoring foot for each part and with the adjacent ends of the two parts suitably secured together.

From the foregoing description of the invention, it is believed that the construction and operation thereof will at once be apparent, and while there is herein shown and described the preferred embodiments of the present invention, it is nevertheless to be understood that minor changes may be made therein without departing from the spirit and scope of the invention as claimed.

What I claim as new is:—

1. In a tie down of the type described, two parts formed of wire, one of which parts is adjusted to be engaged with a part of an automobile, an anchoring foot for each part and the meeting ends of the parts being overlapped and twisted together. 105

2. In a tie down of the type described, two parts formed of wire, one of which parts is adjusted to be engaged with a part of an automobile, an anchoring foot for each part and the meeting ends of the parts being overlapped and twisted together, with the connected twisted ends in line with one part of the tie down. 115

3. A tie down of the type described comprising two parts formed of elongated material with one part longer than the other part, the longer part being adapted for engagement with a part of an automobile, and an anchoring foot for each part, the meeting ends of the two parts being overlapped and secured together against relative longitudinal movements. 120

In testimony whereof I affix my signature.

EDWARD S. EVANS.
